US00D512380S

(12) **United States Design Patent** (10) Patent No.: **US D512,380 S**
Shimizu et al. (45) Date of Patent: **** Dec. 6, 2005**

(54) **ELECTRICAL CONNECTOR**

(75) Inventors: **Kazuomi Shimizu**, Aichi (JP); **Akihiko Onchi**, Aichi (JP); **Daisuke Miyachi**, Aichi (JP)

(73) Assignee: **J.S.T. Mfg. Co., Ltd.**, Osaka (JP)

(**) Term: **14 Years**

(21) Appl. No.: **29/213,864**

(22) Filed: **Sep. 24, 2004**

(30) **Foreign Application Priority Data**

Mar. 26, 2004 (JP) 2004-009148

(51) **LOC (8) Cl.** **13-03**

(52) **U.S. Cl.** **D13/147**

(58) **Field of Search** D13/146-147, D13/199; 439/62, 260, 325, 329, 395, 422, 492, 495, 499, 607

(57) **CLAIM**

The ornamental design for an electrical connector, as shown.

DESCRIPTION

FIG. 1 is a perspective view of an electrical connector showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.
